UNITED STATES PATENT OFFICE.

MILTON J. SHIMER, OF FREEMANSBURG, PENNSYLVANIA.

METHOD OF AND MEANS FOR MANUFACTURING SAD-IRONS.

SPECIFICATION forming part of Letters Patent No. 268,948, dated December 12, 1882.

Application filed October 19, 1882. (No model.)

To all whom it may concern:

Be it known that I, MILTON J. SHIMER, a citizen of the United States of America, residing at Freemansburg, in the county of Northampton and State of Pennsylvania, have invented certain new and useful Improvements in Method of and Apparatus for Manufacturing Sad-Irons and like Articles; and I do hereby declare the following to be a full, clear, and exact description of the invention, such as will enable others skilled in the art to which it appertains to make and use the same.

This invention relates to the manufacture of ironing or sad irons, and has for its objects to make sad-irons by a rapid process, to make the body of the sad-iron of a cheap material, and to make the bottoms thereof of a good and clean metal.

My invention consists, first, in the method or process of manufacturing sad-irons in quick succession, which consists in placing in the mold a prepared bottom for the sad-iron, then closing the mold, then inserting the handle, then pouring in the cast metal to form the body and unite the bottom and handle, then moving the mold forward and automatically dropping the formed sad-iron from the mold.

My invention consists, also, in a metal mold composed of three parts—the bottom, commonly called the "drag," and the vertically-divided top, commonly called the "cope," so hinged to the drag as to open on opposite sides automatically when the mold is inverted.

My invention consists, further, in molds mounted on wheels, in combination with a track and end wheels, over which the molds pass.

My invention further consists in the novel construction and combination of parts, as will be hereinafter more fully set forth.

In the annexed drawings, making a part of this specification, Figure 1 is a side view of a series of connected molds traveling upon a track and over end pulleys, showing the mode of filling the molds and discharging the articles. Fig. 2 is a plan view of a metal mold, showing the bottom plate for the sad-iron in position in the drag and the divided cope open on opposite sides of the drag and a portion of an adjacent mold. Fig. 3 is a side view of a

mold, showing the same in a closed condition, and the handle (indicated by dotted lines) in position. Fig. 4 is a perspective view of a handle for a sad-iron. Fig. 5 is a perspective view of the bottom plate for a sad-iron. Fig. 6 is a perspective view of a complete sad-iron made by my means. Fig. 7 is a perspective view of the traveling mold for making sad-irons, and Fig. 8 is a longitudinal view taken through the line *xx* of Fig. 7.

In carrying out my method or process of manufacturing sad-irons a track is built composed of two rails of a given length and arranged parallel to each other at a desired width. At each end of this track is arranged a transverse shaft carrying a pulley or wheel of a desired diameter and construction adapted to receive the molds from the interposed track and carry them positively around by a suitable motor. The track and end pulleys on the shafts can be supported in any well-known manner, and since I do not confine myself to any special construction of these parts, I deem further detail description unnecessary.

The molds for making the sad-irons are preferably made of metal, and each composed of three essential parts—to wit, the bottom, commonly called the "drag," and the vertically-divided top pieces, commonly called the "cope." The drag *A* is a rectangular frame, with side *b* and end walls, *b* and *c*, side arms or lugs, *d*, and the end sprue-box, *e*. The cope, which is composed of the two sectional pieces *B* *B'*, has its sides and ends beveled to fit the correspondingly-beveled sides and ends of the drag. On the under side of these pieces *B* *B'*, composing the cope, is worked the outlines or configuration of the body of a sad-iron, as shown in Figs. 2 and 8 of the drawings, and formed with the notches *f* for the passage of the prongs of the handle. The upper surface of these pieces *B* *B'* (see Figs. 3, 7, and 8) is formed with lugs *h*, centrally located between which are pivoted the curved arms *C* *C'*, pivotally connected to the lugs *i* on the sides of the drags.

Through the perforations in the side arms, *d*, of the drag are passed the transverse rods *k*, carrying at the ends the wheels *m*, preferably grooved. To connect the molds together,

so as to cause them to follow each other, the arms *d* of the adjacent molds are overlapped, as seen in Figs. 1, 2, and 7 of the drawings, and the rods passed through the registered 5 perforations of the arms, thus making an axial coupling.

The letter D (see Fig. 5) represents the bottom plate for a sad-iron, with a surrounding flange and a plurality of connecting-studs. 10 This plate is made of clean and good iron, that is easily polished.

The connected molds, with two uncoupled, are mounted on the track and placed around the wheels, and the two uncoupled molds connected, so as to form an endless series of molds. 15 As the molds are moved forward, as indicated by the arrow in Fig. 1, the bottom plates are placed in the drags by an attendant as each mold rises and is about to assume a horizontal position, preferably after the left-hand section, B, of the cope has dropped into position, and before the right-hand section, B', has dropped into position. After one of the cope-sections is down it forms an excellent guide, on account of the mold configuration for the body 20 of the sad-iron, for the adjustment of the bottom plate within the mold. After the bottom plate is properly adjusted within the mold the other or right-hand section of the cope is permitted to drop into position and close the mold. 25 The loose handle E, (see Fig. 4,) having its prongs preferably notched for better anchorage, is inserted through the openings *f* in the sectional cope until the ends rest upon the bottom plate, or nearly so, in which vertical position the handle is sustained. This mold is now moved forward by the proper 30 power under the supported ladle, containing molten metal, which may be of a common quality, and by tilting the ladle the metal is run into the sprue-box and through the gate into the mold, filling the same, thus uniting the bottom plate and the prongs or ends of the handle with the cast-iron composing the 35 body of the sad-iron. The filled mold is now moved forward and the next prepared connected mold brought under the ladle, and as the filled molds are moved forward and over the wheels the sectional copes automatically 40 open on opposite sides and permit the molded sad-irons to drop out, as indicated by the sad-irons 1 and 2 in Fig. 1 of the drawings. The 45 operation is thus continued and repeated, pro- 50

ducing the sad-irons in a greatly-increased rate of production. The bottoms of the sad-irons are now polished and finished in the usual manner. 55

I reserve the right to vary the construction and arrangement of parts without departing from the spirit of my invention, and vary the 60 shape of the molds for sash-weights and dumb-bells, and the like.

The sad-iron herein described, and shown in Figs. 4 and 6 of the drawings, will form the 65 subject-matter of a separate application.

What I claim as my invention, and desire to secure by Letters Patent, is—

1. The improvement in the art of manufacturing sad-irons, which consists in arranging in the mold a prepared bottom for the sad-iron, 70 then closing the mold, then inserting the handle, then moving the mold forward and automatically discharging the shaped sad-iron, substantially as described.

2. In the manufacture of sad-irons, a metal 75 mold composed of the drag and the vertically-divided cope hinged on opposite sides of the drag, constructed to open automatically when inverted, substantially as described.

3. A series of traveling molds with hinged 80 copes mounted on wheels and constructed to open automatically when inverted, in combination with a track and end pulleys with suitable driving mechanism, substantially as described. 85

4. In combination with a drag formed with end lugs, *i*, a vertically-divided cope formed with lugs *n*, and connecting-arms *C*, substantially as described.

5. The combination, with a mold-drag formed 90 or provided with ends or extensions *d*, forming bearings, of axles *k* and wheels *m*, substantially as and for the purpose set forth.

6. An improved traveling mold for castings, consisting of the drag formed or provided with 95 ends or extensions *d* and lugs *i*, the divided cope *B* *B'*, with lugs *n*, connecting-arms *C*, axles *k*, and wheels *m*, substantially as described.

In testimony whereof I affix my signature in 100 presence of two witnesses.

MILTON J. SHIMER.
